REFRIGERATING APPARATUS

Alex A. McCormack, Dayton, Ohio, assignor to
 General Motors Corporation, Dayton, Ohio, a
 corporation of Delaware

Application August 29, 1934, Serial No. 741,967

4 Claims. (Cl. 230—147)

This invention relates to refrigerating apparatus and more particularly to a rotary fluid compressor adapted for use in a refrigerating machine of the compressor-condenser-expander type.

It is an object of the invention to provide a rotary fluid compressor having a novel sealing mechanism for maintaining a fluid tight joint between the impeller and the divider block which divides the compression space from the suction space.

It is also an object to provide a rotary fluid compressor having a novel sealing mechanism for the surface between the end wall of the cylinder and the impeller which permits the compressor to be operated by a motor located outside the refrigerant circuit and which avoids the use of seals having a running joint.

Further objects and advantages of the present invention will be apparent from the following description, reference being had to the accompanying drawings, wherein a preferred form of the present invention is clearly shown.

In the drawings:

Fig. 1 is a side view of a refrigerating apparatus embodying the present invention;

Fig. 2 is a vertical cross section of the compressor mechanism of the present invention;

Fig. 3 is a fragmentary cross section on line 3—3 of Fig. 4;

Fig. 4 is a cross section on line 4—4 of Fig. 2;

Fig. 5 is a cross section on line 5—5 of Fig. 2; and

Fig. 6 is a fragmentary end view of the mechanism shown in Fig. 2.

Referring now to Fig. 1, there is illustrated a refrigerating apparatus comprising a motor 10, having a shaft 12 for driving a compressor 14 and fan 16. The compressor 14 is adapted to deliver compressed refrigerant by means of a conduit 18 to a condenser 20 over which air is circulated by the fan 16. A conduit 22 delivers refrigerant liquefied in the condenser to an expansion valve 24 where it is admitted to an expansion coil 26 for vaporization therein for the purpose of withdrawing heat from a cabinet or other object to be cooled. The compressor 14 withdraws the vaporized refrigerant from the expansion coil 26 through a conduit 28. The parts thus far described constitute the customary elements of a refrigerating apparatus, herein illustrated diagrammatically rather than in detail.

The compressor mechanism preferably comprises a rotary compressor of the general type which includes a body member formed of a cylinder 30 and end plates 32 and 34 secured there-

to by bolts 35. Within the body member, there is mounted a cylindrical impeller 36 which is caused to revolve in the cylindrical chamber of the body member without rotating by means of an eccentric 38 formed on or secured to the shaft 12. The space within the body member 30 is divided into a compression chamber 40 and a suction chamber 42 by means of a divider block 44 which is mounted for reciprocation in a slot 46 formed in cylinder 30 and is urged toward the impeller 36 by means of springs 48.

In order to provide an efficient long lasting sealing surface between the divider block 44 and the impeller 36, a facing or sealing member 50 is secured to the end face of the divider block 44 in a suitable manner, such as by being dovetailed thereto as illustrated. The member 50 is formed of a resilient rubber-like material which is not deteriorable by the common refrigerants and lubricants. At one side of the divider block 20 in the end plate 34 is formed an inlet aperture 52 to which is mounted an inlet fitting 54. At the opposite side of the divider block 44 an exhaust aperture 56 is formed in the plate 34 and has at its outer end a valve seat formed thereon. 25 A flapper valve 58 of usual construction coacts with the seat to act as a check valve for the outlet from the compressor. A valve housing 60 is secured to the outer face of the plate 34, as by bolts 62, and encloses the flapper valve 58. An 30 outlet fitting 64 is secured to the valve housing 60 to communicate with the space inside the housing 60.

In order to provide an impervious hermetic seal between the compression space and the outside of the compressor, the impeller 36 is formed with a shouldered recess 66 at either side thereof, adjacent its central opening. Portions of the impeller are cut away as at 68 for a purpose that will be apparent hereafter. Similar shouldered recesses 70 are formed in the inner face of the end plates 32 and 34 and associated therewith are cut-away portions 72 similar to the cut-away portions 68. At each side of the compressor, there is mounted in the shouldered recesses 66 and 70, a cylindrical sealing sleeve 74 of a flexible and resilient rubber-like material which is not deteriorable by the well known refrigerants and lubricants. The facing member 50 on the divider block 44 is preferably formed of the same material which may comprise, for example, a polymer of chloro 2-butadiene 1,3 known in the trade as "Duprene" or "Chloroprene". The sleeves 74 are hermetically sealed to the shoul- 50 55

dered recesses 66 and 70 by expandible clamping rings 75.

In operation, the motor 18 may be energized under the control of a suitable automatic switch (not shown) and causes rotation of the shaft 12 which in turn actuates the impeller 36, causing it to revolve in the body member 30 without rotating. The motion of the impeller 36 causes withdrawal of refrigerant fluid from the evaporator 26 through the suction aperture 52 and compresses the fluid delivering it through the exhaust aperture 56 as is well known in compressors of the general type described. The flexible resilient facing member 50 is tightly pressed against the impeller 36 by the springs 48 and provides a gas tight seal between the compression space 40 and the suction space 42 due to its resilience which permits the impeller 36 to deform the surface of the facing member 50, causing a wide area of contact. Also, due to the resilience of the facing member 50, it conforms to any slight irregularities which may be present in the contour of the impeller 36, thus materially improving the tightness of the seal at that point and maintaining this condition throughout the useful life of the compressor. The sealing sleeves 74 being flexible follow the revolving movement of the impeller 36 and being impervious provide a hermetic seal for the compression space within the body member 30. Inasmuch as the flexible resilient material of the sealing members 50 and 74 is not deteriorated in the presence of the common refrigerants and lubricants, the compressor operates efficiently and without substantial leakage over long periods of use. This feature is particularly useful in a refrigerating system employing as a refrigerant a fluorine derivative of a hydrocarbon, for example dichlorodifluoromethane and as a lubricant a mineral oil wherein great difficulty is encountered in preventing leakage across metal to metal contacts and wherein the use of rubber is prevented by the rapid deterioration thereof caused by the refrigerant and lubricant.

It will thus be seen that there has been provided a rotary compressor in which a gas tight seal will be maintained satisfactorily throughout a long period of useful life, not only at the surface between the divider block and the impeller, but also for the surface between the impeller and the end walls of the cylinder within which it revolves. The latter seal is hermetic in that there are no running joints involved in this construction, and it, furthermore, permits actuation of the compressor by means of a shaft which is external to the compression space of the compressor. In other words, the present invention provides the advantages of a hermetically sealed compressor unit which include the elimination of stuffing boxes or other running joints for shaft seals and the consequent avoidance of leakage of refrigerant, and yet avoids the disadvantage of

having to locate the motor within the hermetically sealed portion of the compressor. Furthermore, the invention provides a compressor eminently suited for the efficient compression of refrigerants comprising fluorine derivatives of hydrocarbons.

While the form of embodiment of the invention as herein disclosed, constitutes a preferred form, it is to be understood that other forms might be adopted, all coming within the scope of the claims which follow.

What is claimed is as follows:

1. A pump including a casing having an annular wall forming a cylinder and end walls therefor and having fluid inlet and outlet ports, a piston means fitting within said walls to form a pumping chamber, said piston means being smaller than the cylinder, means for revolving said piston means eccentrically within the cylinder for pumping fluids into and out of the pumping chamber, and a plurality of sleeves formed of gas-tight flexible material impervious to said fluids, each of said sleeves having one end immovably connected to an end of said piston means and the other end immovably connected to the adjacent end wall of the casing to provide a hermetic seal between both ends of said piston means and the casing and to secure said piston means against rotation.

2. A pump according to claim 1, in which the sleeves are substantially the same in size and are symmetrically located to balance the fluid pressures upon the piston means.

3. A pump according to claim 1, in which the end walls of the casing and the ends of the piston means are formed with cut-away portions to provide spaces surrounding said sleeves.

4. A pump including a casing having an annular wall forming a cylinder and end walls therefor and having inlet and outlet ports, piston means fitting within said walls to form a pumping chamber, the piston means being smaller in transverse section than the cylinder and having contact with one of said end walls in all operative positions of the piston means, means for revolving the piston means eccentrically within the cylinder for pumping fluids into and out of the pumping chamber, and a sleeve formed of gas-tight material impervious to said pumping fluids, said sleeve having one end immovably connected to said one end wall and the other end immovably connected to the adjacent end of the piston means to provide a hermetic seal between said adjacent end of the piston means and said one end wall of the casing and to secure the piston means against rotation, and said adjacent end of the piston means and said one end wall of the casing being formed with cut-away portions to provide a space surrounding said sleeve.

ALEX A. McCORMACK.
